UNITED STATES PATENT OFFICE.

SAMUEL SADLER, OF ST. LOUIS, MISSOURI.

DESIGN FOR A WASHING-MACHINE TUB.

SPECIFICATION forming part of Design No. 21,997, dated November 15, 1892.

Application filed June 21, 1892. Serial No. 437,522. Term of patent 14 years.

To all whom it may concern:

Be it known that I, SAMUEL SADLER, of St. Louis, in the State of Missouri, have invented and produced a new and original Design for 5 a Washing-Machine Tub, of which the following is a full, clear, and exact description, reference being had to the accompanying drawings, forming a part hereof.

Referring to the drawings, Figure 1 is a 10 side elevation of a tub embodying my design, and Fig. 2 is an inverted plan view of the same.

The leading feature of my design is an 15 ornamental pair of bodies 2, each having an outline in the similitude of a triangle when viewed in side elevation and projecting in relief from the exterior surface of the tub 1, with the opposite edges 3 of each triangular body in such relation to the conical body of 20 said tub that such edges present the appearance to the eye of the observer of lying parallel with the exterior outline 4 of said coni-

cal body, as shown in Fig. 1. The lower terminals 5 of the bodies 2 are rounded, while their upper corners are pointed, as indicated 25 at 6. The above-described ornamentation presents to the eye of the observer an appearance of symmetry and finish, which would not be apparent if the edges of the bodies 2 were located at an acute angle to the outline 30 4 of the conical body. The upper edges of the bodies 2 are parallel with the base of the conical body, and projecting centrally from the upper edge of each is a vertical figure 7, having a pointed upper terminal. 35

What I claim is—

The design for a washing-machine tub, as herein shown and described.

In testimony whereof I affix my signature in presence of two witnesses.

SAMUEL SADLER.
